WILBUR G. LAIRD, OF PLEASANTVILLE, NEW YORK, ASSIGNOR TO DOHERTY RESEARCH COMPANY, OF NEW YORK, N. Y., A CORPORATION OF DELAWARE

GAS HOLDER

Continuation of application Serial No. 93,114, filed March 8, 1926. This application filed May 25, 1931. Serial No. 589,740.

This invention relates to gas holders and more particularly to those of the water sealed multiple-lift type.

This invention was originally described in 5 my previously filed application Serial No. 93,114 filed March 8, 1926, of which this is a full continuation.

The type of gas holder in most common use, consists of a tank or water reservoir in which 10 one or more lifts or bells are constructed in such a manner that as the gas is introduced into the holder the lift is elevated and the gas is prevented from escaping by means of the liquid seal at the lower edge of the lift.

15 For the storage of large volumes of gas in holders of this type, it is common practice to employ the multiple-lift principle as offering a less expensive unit per cubic foot of gas storage capacity. This is explained by the 20 fact that the tank of the holder is the most expensive part of the unit because it must be constructed of material sufficiently strong to withstand the hydrostatic head of the sealing liquid, whereas, the lifts are subjected to 25 bursting strains based on gas pressures sufficient only to elevate them against their own dead weight; such pressures being very much less than those produced by the static head of the sealing liquid in the tank.

30 In the application of the multiple-lift principle, the inner or top lift is constructed in a manner similar to a single lift except that its lower edge is provided with a "cup" which engages the "grip" of the second or 35 adjacent lift of a series of lifts. Each intermediate lift is provided with a "cup" at its lower edge and a "grip" at its upper edge so as to provide a liquid and gas tight seal between the lift sections. The nesting of the lifts in 40 the tank enables the use of a plurality of telescopic sections approximately equal in height to the depth of the tank and which, when fully elevated, provide a gas storage capacity which may approximate the storage capacity 45 of the inner lift multiplied by the number of lifts. Thus one expensive tank is utilized to function in conjunction with a plurality of less expensive lifts or telescopic sections wherein the gas is stored. Each lift or section 50 as it is lifted above the tank by the gas

pressure exerted against the crown of the inner lift, is coupled to the next outer lift and the two lifts so coupled act in their elevation thereafter as a single lift; therefore the telescoping of the lifts as they are lowered 55 and come to rest in the tank may be likened to the folding or disjointing of a single lift of similar height.

In a multiple-lift holder, it is obvious that the guide-frame provided for guiding the vertical movement of the lifts, must be of a height sufficient to act as a guide for all of the lifts and that it must be strong enough to support the lifts against all wind strains and normal tipping. Furthermore, the guide-frame 60 at all times must be truly vertical in order to maintain the level of the liquid seal in the elevated cups in a horizontal plane. This guide-frame is a large and unsightly structure; constitutes a large percent of the total 65 cost of the installation; and due to its type of construction and exposed and elevated character, is costly to maintain. Moreover, any slight foundation settlement or other misalignment is apt to result in guide-frame 70 warpage which may cause the lifts to jamb and the installation to be seriously injured. In fact, many cases are on record where foundation settlement has so deflected the guide-frame that the holder could not be operated until much time and money had been 75 expended in realignment.

The primary object of the present invention is to provide a means whereby the vertically 80 movable lifts may be held in proper alignment without employing the usual heavy and expensive guide-frame.

Another object of the invention is to provide a guiding means which will permit lifts to be installed in practically any type of 85 tank without requiring special foundation work or other alterations for accommodating a special guide-frame.

Another object of the invention is to provide a means for guiding the lifts of a holder 90 which may be contained within the holder and protected from climatic conditions involving atmospheric oxidation and corrosive reactions.

Another object of the invention is to pro- 100

vide a guiding means for a gas holder which will permit of quick and easy alignment of the lifts in the event of foundation settlement and tank warpage.

5 Further objects of the invention are to provide a guiding means for a gas holder that is simple and inexpensive to install; is easy to keep in proper adjustment and repair; and makes the holder unit more attractive 10 in appearance.

With these and other objects in view the invention consists in the improved guiding means for a multiple-lift gas holder as hereinafter illustrated and claimed.

15 The various features of the invention are illustrated in the accompanying drawing, in which:

Fig. 1 is a plan view of a multiple-lift gas holder embodying a preferred form of the 20 invention, and

Fig. 2 is a vertical sectional view of the gas holder shown in Fig. 1.

The lift guiding means embodying the preferred form of the invention comprises a series of cables, ropes, chains or other flexible members arranged to support and guide the lifts and to hold the lifts in their proper alignment. Each cable connects all of the lifts together and its ends are secured to the tank in such a manner that the lifts will be constrained to move in vertical paths and in their proper sequence.

In the drawing is illustrated a common form of multiple-lift gas holder comprising lifts 10, 12 and 14 mounted to move up and down in a tank 16 containing a liquid seal. The bottom of the lift 10 is provided with a cup 18 arranged to receive a grip 20 secured to the top of the lift 12. The cup 18 is normally supplied with water from the tank so that when the grip 20 is in cup 18 a gas tight seal is formed between lifts 10 and 12. A cup 22 formed around the lower edge of the lift 12 is arranged to receive a grip 24 secured to the top of lift 14. A body of water is always maintained in the cup 22 so that when the grip 24 is in the cup 22 a gas tight seal is formed between lifts 12 and 14. The lift 14 always remains in part or wholly within tank 16 so that its lower edge is sealed by a body of water the level of which is indicated by the dotted line 26. Spacing rollers 23 (Fig. 1) mounted on the inner rim of tank 16 between the tank and lift 14, serve to hold the outer periphery of the lift in properly spaced relation to the inner periphery of the tank, while other spacing rollers 25 (Fig. 2) mounted on the outer rim of each lift cup function to maintain in the nested lift segments in properly spaced positions.

When there is a small amount of gas in the holder the lifts move down into the tank with their lower edges resting upon rest blocks 28. In this position all of the gas is

held in the lift 10, such gas being introduced by a pipe 30 and withdrawn through pipe 32. As the gas fills the holder the lift 10 rises until it makes connection with the lift 12 then the lifts 10 and 12 rise together until lift 12 connects with lift 14 and then all of the lifts 10, 12 and 14 rise together. As the gas passes out of the holder the lifts move down in the reverse order from that described above.

The cables for guiding the lifts in the above described movement are arranged in pairs spaced around the periphery of the lifts and preferably extending diametrically across the lifts. Each pair of cables is mounted and operated in the lifts and tank in substantially the same manner. Therefore the construction, mounting and operation of only one pair of cables will be described.

One cable 34 of each pair is secured to a hanger 36 mounted on the rim of the tank 16, then passes down to the bottom and under pulleys 38 and 40, then up to a pulley 42 mounted under the crown of the lift 10, then passes diametrically across the lift 10 to pulley 44, then passes down and under a pulley 46 mounted on the bottom of the cup 18 of the lift 10, then passes up over a pulley 48 mounted on the top of grip 20 of lift 12, then passes down under a pulley 50 mounted on the bottom of cup 22 of lift 12, then passes up over a pulley 52 mounted on the top of grip 24 of lift 14, then passes down and under a pulley 54 mounted on the bottom edge of lift 14, then passes up adjacent the wall of the tank 16 to a bracket 56 mounted at the brink of the tank diametrically opposite the hanger 36. At the surface of the water 26 the cable 34 may be in the form of a chain 58 to better resist the corrosive action at the place where the cable emerges from the water. The cable 34 is attached to the bracket 56 by means of a bolt 60 which passes through a compression spring 62, the spring acting to maintain the cable taut. The other cable 64 of the pair has one end secured to a hanger 66 mounted adjacent the bracket 56 then passes down to the bottom of the tank under pulleys 68 and 70, then passes up and over a pulley 72 mounted under the crown of the lift 10 adjacent pulley 44, then passes diametrically across the lift to a pulley 74 adjacent pulley 42, then passes down under a pulley 76 mounted on the bottom cup 18 of lift 10, then passes up to a pulley 77 mounted on the grip of lift 12, then passes down and under a pulley 78 mounted on the bottom of the cup 22 of lift 12, then passes up and over a pulley 80 mounted on the grip of lift 14, then passes down and under a pulley 82 mounted on the bottom edge of lift 14, then passes up to a bracket 84 mounted on the rim of tank 16 adjacent the hanger 36. The cable 64 is attached to the bracket 84 by means

of a bolt 86 which passes through a compression spring 88. The cables 34 and 64 are arranged in substantially parallel positions. These cables move in opposite directions as the lifts move up and down. From the hanger 36 to the pulley 40 and from the hanger 66 to the pulley 70 the cables do not move as the lifts move but this construction is used to permit the cables to be readily replaced, repaired or inspected. To replace a guiding cable a new cable is attached to the old guide cable and is drawn into position as the old guiding cable is withdrawn.

In the drawing only two pairs of cables have been illustrated but it is preferred to use many pairs of cables which may preferably be uniformly spaced around the periphery of the lifts.

The cables are preferably mounted on the inside of the tank and lifts whereby the pulleys and cables are protected from atmospheric oxidation and seasonal storms, corrosion and other conditions which interfere with the operation of the machinery. The pulleys 48, 52, 77 and 80 are mounted on the outside of the lifts but are inside of split sealed housings which communicate with the interior of the lifts.

By arranging the guiding cables as illustrated and described above the lifts are effectively supported and guided. The pairs of cables act to effectively hold the lifts against the side wind pressure and confine the movement of the lifts to vertical paths.

35 The invention having been thus described, what is claimed as new is:

1. In a gas holder, a tank, a plurality of lifts independently movable over the tank, and a guide means for the lifts comprising, 40 cables mounted entirely within the tank and lifts, with their ends attached to the tank at opposite sides thereof, said cables connecting all of the lifts together.

2. In a gas holder, a tank, a plurality of lifts independently movable over the tank and a guide means for the lifts comprising cables mounted on guides so as to move wholly within the lifts with their ends attached to the tank at opposite sides thereof, said cables 45 connecting all of the lifts together and arranged to constrain the walls of the lifts to move up and down in vertical paths, and liquid seal connecting devices between the lifts arranged with said cables to provide 50 for movement of the lifts in succession.

3. In a gas holder, a tank, a plurality of lifts independently movable over the tank and a guide means for the lifts comprising cables mounted within the lifts, each cable 55 having one end attached to the tank, then passing over pulleys attached to the lifts and passing in a path substantially parallel to the walls of the lifts, then across the top of the top lift and then down to the tank with 60 its end attached thereto.

4. In a gas holder, a tank, a plurality of lifts independently movable over the tank and a guide means for the lifts comprising cables mounted within the lifts and arranged in pairs extending substantially diametrically across the tank, each cable having one end attached to the tank, then passing over pulleys attached to the lift in a path substantially parallel to the walls of the lifts, then across the top of the top lift, and then down and having its other end attached to the tank, one cable of each pair running parallel to the walls of the lifts at one side thereof, and the other cable running parallel to the walls of the lifts opposite the position of the first cable.

5. In a gas holder, a tank arranged to provide a body of sealing liquid, a gas storage member having a plurality of nested telescopic lifts movably mounted in the tank with its side walls sealed by the sealing liquid so as to trap gas under the crown of the top lift above the sealing liquid, and guide means for the member comprising flexible cables secured to the tank and guidably connected to the upper and lower parts of the member and movably mounted wholly within said tank and storage member.

6. In a gas holder, a tank arranged to provide a body of sealing liquid, a gas storage member having a plurality of nested telescopic lifts movably mounted in the tank with its side walls sealed by the sealing liquid so as to trap gas under the crown of the top lift above the sealing liquid, and guide means for the member comprising a plurality of flexible cables each guidably connected to the member at spaced points around the inner circumference thereof and mounted within said tank and member, each cable having its ends secured respectively to the top and bottom of the tank and being movable intermediate its ends over pulleys attached respectively to the upper and lower parts of each telescopic lift of the storage member.

7. In a gas holder, a tank arranged to provide a body of sealing liquid, a gas storage member having a plurality of nested telescopic lifts movably mounted in the tank with its side walls sealed by the sealing liquid so as to trap gas under the crown of the top lift above the sealing liquid, guide means for the member comprising flexible cables distributed in pairs and each having their ends secured to the tank at diametrically opposite points, said cables being mounted wholly within said tank and member on pulleys attached to the upper and lower portions of each lift.

8. In a gas holder, a tank arranged to provide a body of sealing liquid, a gas storage member having a plurality of nested telescopic lifts movably mounted within the tank with its side walls sealed by the sealing liquid so as to trap gas under the crown of the top

- lift above the sealing liquid, guide means for the members comprising flexible cables operatively connected to the tank and to the upper and lower parts of the member and mounted
5 within the tank and member, spacing rollers mounted between the inner periphery of the tank and the outer periphery of the outside lift, and other spacing rollers mounted between each adjacent pair of lifts.
10 In testimony whereof I affix my signature.
WILBUR G. LAIRD.
